PORTFOLIO

Samuel Segal, New York, N. Y., assignor to Wilson-Jones Co., Chicago, Ill., a corporation of Massachusetts

Application July 5, 1947, Serial No. 759,106

1 Claim. (Cl. 281—29)

1

The present invention is directed to portfolios of the type adapted to carry and conceal a ring type loose leaf binder. The chief object of the invention is to permit the use of a single portfolio with several loose leaf binders severally adapted to be mounted within the portfolio and to this end an ancillary object is concerned with the provision of spaced keepers on the portfolio for detachably interlocking with a loose leaf binder. More specifically the invention has for an object the provision of spaced and fixed keepers simultaneously adapted to be initially received within relatively enlarged openings of spaced compound slots in a loose leaf binder whereby spaced sides of rectilinear openings of the compound slots are awaiting to straddle the keepers and be arranged under overhanging lips thereof for slidably interlocking with the keepers upon shifting the binder longitudinally thereof after which liftable locking means carried by the binder automatically operates to cooperate with one of the keepers to preclude displacement of the binder relative to the portfolio. A further and specific object is concerned with automatically retractable detent means carried by the loose leaf binder and overhanging a major portion of one of the compound slots thereof and adapted to be automatically elevated on mounting the binder on the spaced keepers fixedly carried by the portfolio. Another object comprehends the utilization of a conveniently accessible manipulator for elevating one end of the tiltable detent means to permit slidable displacement of the binder relative to the portfolio preparatory to detaching the former from the portfolio.

In the accompanying drawings:

Fig. 1 is a plan view of a portfolio illustrating the loose leaf binder according to one embodiment of my invention attached thereto and shown fully closed.

Fig. 2 is a transverse sectional view on the line 2—2 of Fig. 1.

Fig. 3 is an enlarged sectional view on the line 3—3 of Fig. 1.

Fig. 4 is a fragmentary and exploded view of Fig. 1 exhibiting the loose leaf binder detached from the spaced keeper means attached to the portfolio.

Fig. 5 is a fragmentary view of Fig. 2 however showing the binder in an unlocked relation with one of the keeper means and awaiting to be withdrawn therefrom.

Fig. 6 is a view similar to Fig. 5 however illustrating in full lines the tiltable locking detent in its retracted position and cooperating to pre-

clude shifting of the binder relative to the portfolio.

Fig. 7 is a sectional view on the line 7—7 of Fig. 6.

Fig. 8 is an elevational view of one of the rivets or keeper means.

Fig. 8a is a perspective view of one of the keeper means and an associated annular clamping member.

Fig. 9 is a perspective view of a portfolio and another form of binder attached thereto.

Fig. 10 is a sectional view on the line 10—10 of Fig. 9.

Fig. 11 is a sectional view on the line 11—11 of Fig. 10.

Fig. 11a is a bottom view of the binder shown in Fig. 10 but on a smaller scale and

Fig. 12 is a sectional view on the line 12—12 of Fig. 11.

20 Advantageously fastened to the portfolio P is the relatively sturdy leather wall 10 defining with the outside leather body 11 of the portfolio the storing compartment 12.

Anchored by spaced rivets or keeper means 14 to the wall 10 (Figs. 2 and 4) is the leather strip or backing 15. Specifically each rivet 14 is provided with an annular flange 16 adapted to be seated on the leather strip 15. About the shank of each rivet 14 and held against the compartment or pocket wall 10 by head 17 of the rivet is the annular washer 18. By the present arrangement it is apparent that the strip 15 is firmly clamped against the pocket wall 10 by an annular flange 16 and a companion annular washer 18.

35 Integral with annular and overhanging flange 16 and extending upwardly therefrom is the reduced web 19 (Fig. 8) having the spaced rectilinear sides 20 and defining with the overhanging lips 21 of the annular head as of the rivet 14 spaced channels, grooves or tracks 23.

40 The circular head 22 of the studs or rivets 14 are smaller than the enlarged expanded and spaced circular openings 25 at corresponding ends of compound slots generally each denoted 26 and each having a reduced and rectilinear opening 27 in communication with its companion circular opening 25. Preferably the compound slots 26 are disposed in the bottom arcuate plate 28 of a conventional ring type loose leaf binder generally indicated RTB for removably holding a stack of perforated sheets of papers (not shown) and adapted as is customary to be opened and closed by operating the triggers 29.

45 With the enlarged or expanded openings 25 receiving the upper ends of the rivets or keeper

means 14 and more particularly the heads 22 thereof, the spaced portions 30 constituting the rectilinear sides of the reduced openings 27 of the compound slots 26 are in alinement with spaced gaps 23, and hence the binder may be slidably and bodily displaced in the direction of the arrow 31 (Fig. 5) whereby sides 30 of the compound slots move under lips 21 and simultaneously straddle the webs or intervenors 19 of the keepers 14, thus interlocking therewith. However when the ends 32 of the restricted openings 27 are near the keeper means, the binder is locked against linear displacement due to the action of the self retracting locking detent generally indicated D comprising a relatively flat and flexible leaf spring 35 and the superimposed cold rolled and non-flexible bar or lever 36 provided with a fixed manipulator or button 37 normally projecting in part through opening 38 in the upper arcuate cover plate 39 of the loose leaf binder RTB.

Lever 36 is secured to one end of the leaf spring 35 by rivet 40 and the other end of the leaf spring 35 is anchored to the bottom wall 28 of the binder by the rivet 41. Normally spring 35 holds the detent retracted, that is, substantially horizontal as shown in Figs. 6 and 7 and against the wall 28 of the binder to permit the front end FE of the detent to overhang the adjacent expanded opening 25 and an associated communicating reduced opening 27 of the compound slot 26.

Upon insertion of the heads 22 of the spaced keeper means 14 into the enlarged openings 25, one of the heads 22 automatically tilts the detent D (Fig. 5) causing the front end FE to be automatically raised thereby causing the other end BE thereof to be biased or tilted downwardly into relief opening 42 in the hollow wall 28. Or in other words, detent D unlocks automatically. As the binder is moved in the direction of arrow 31 and under the lips 21 of heads 22 of the spaced keeper means, detent D automatically is urged to assume a substantially horizontal position due to the retractive action of the leaf spring 35. Consequently when the head 22, tilting the detent, clears the front end FE, the detent automatically and fully retracts and drops into the path of the adjacent keeper, thus constituting a stop (Figs. 6 and 7) precluding slidable displacement of the binder relative to the portfolio, that is, the binder is locked against slidable displacement and against removal from the portfolio. To detach the binder from the portfolio, manipulator 37 is depressed as shown in Fig. 6 by the dash and dot line position, thereby elevating the forward end FE of the detent D above the elevation of the companion head 22 of the associated keeper means which is then adapted to be slidably displaced to unlock from the walls 30 and eventually the heads of the spaced keeper means arrive to be within the spaced openings 25 at which time the binder may be lifted and be disengaged therefrom or in other words from the portfolio.

In the form according to Figs. 9 to 12, the locking detent D' is characterized by a metal leaf spring 50 having end BE' secured by rivet 51 to the outside face of the arcuate bottom 28 of the binder and its intermediate portion thereof is disposed longitudinally across the enlarged opening 52 in the bottom wall 28 while its free end FE' is normally seated on the spaced stop lips 53 at the junction of the opening 52 and the communicating rectilinear opening 54 also

in the bottom wall 28. Spring 50 fixedly carries the knob or manipulator 55 projecting through and above opening 56 in the cover 39 of the binder.

In Fig. 10, the binder may be considered locked to the portfolio as the rectilinear sides of the slot 54 are interlocked with adjacent head 22 of one of the spaced keeper means while the head of the other keeper means is interlocked with side walls as 30 of the opening 27 at the other end of the plate 28, as is well understood, at which time the free end FE' of the normally depressed detent D' is in line with an adjacent head 22 of the keeper means 14 and acts as a stop to preclude slidable displacement of the binder relative to the portfolio even though, as in the embodiment according to Figs. 1-8, the binder is interlocked with the keeper means.

To unlock detent D', the operator merely lifts manipulator 55 upwardly, causing end FE' to rise appreciably above the adjacent head 22, thus unlocking in part the binder and the latter may be slidably moved to the right relative to the portfolio and eventually heads 22 simultaneously reach the enlarged openings 25 and 52 (Fig. 11^a) and the binder may be lifted from the portfolio. Thereafter upon removal of the finger pressure from manipulator 55, leaf spring 50 retracts against the stop lips 53 awaiting to be again raised by one of the keeper means 22 when the binder is again attached to the portfolio. Of course the operator may unlock detent D' from the adjacent keeper by lifting the detent upwardly by a finger inserted under end opening 57 in the pocket wall 10. In other aspects the embodiment according to Figs. 9-12 is along the lines of the form shown in Figs. 1-8 and in all the forms disclosed, the middle ring MR when attaching the binder is first lined up with the datum line or index means 60 for automatically positioning the spaced keepers in alinement with the circular openings 25 of the compound slots 26 for simultaneous and expeditious reception thereby.

Briefly recapitulating, in all the forms disclosed a normally retracted locking detent overhangs a major portion of an elongated and compound slot 26, for example, in Fig. 11 defined by the communicating openings 52 and 54 and in Fig. 4 by the communicating openings 25 and 27. In each case, the detent is adapted to be automatically tilted on mounting the binder on the spaced keepers 14, that is, when the latter are received by the enlarged portions 25 of the compound slots. By such action one of the keepers tilts or elevates one end of the detent and holds the latter elevated until corresponding ends as 32 of the narrow openings 27 have reached the spaced keepers at which time the detent means snaps back to be in alinement with or in the path of an adjacent keeper, thus acting as stop means to prevent longitudinal displacement of the binder relative to the portfolio.

Various changes may be made in details of construction and arrangement of parts without departing from the spirit of the invention or sacrificing any of the advantages thereof inherent therein.

I claim:

In a device of the character described, a portfolio having spaced keepers each comprising a head having a web and overhanging lips, a loose leaf binder provided with a bottom wall and a top wall, said bottom wall having spaced compound slots embodying relatively large openings

for removably receiving said heads and embodying reduced openings defining spaced and rectilinear sides for removably straddling said web and adapted to be disposed under said lips upon displacement of said binder relative to said portfolio, a spring detent carried by said binder and in part overhanging one of said slots the spring action of said detent moving it into engagement with the edge of one of said keepers upon longitudinal displacement of said binder relative to said portfolio from the position in which said binder and portfolio are initially engaged, to hold said binder and portfolio against relative longitudinal displacement in the opposite direction, and a stud projecting from said detent through said top wall, said stud being operable to disengage said detent from keeper, whereby said

binder may be released from interengagement with said portfolio.

SAMUEL SEGAL.
